BREATHING APPLIANCE

Robert Henry Davis, London, England

Application December 22, 1931, Serial No. 582,624
In Great Britain October 15, 1931

3 Claims. (Cl. 128—191)

This invention is for improvements in or relating to breathing appliances adapted more especially for submarine use, of the self-contained type comprising a breathing bag in the form of an inflatable envelope of rubber or the like, a mouthpiece preferably having means whereby it may be attached to the head of the person wearing the appliance, a breathing tube connecting the mouthpiece and breathing bag, means for absorbing carbon dioxide from the exhaled air and means for admitting a charge of oxygen to the interior of the breathing bag, for example, an oxygen cylinder forming a part of the appliance and provided with a valve controlled connection with the breathing bag.

It is a difficulty with appliances of this type, that the wearer, when he reaches the surface of the water, may be in an unconscious condition or too unwell to close the shut-off valve of the breathing bag (usually provided in the mouthpiece of the appliance) and thereby convert this bag into a buoyancy chamber in the usual way (the wearer thereafter breathing from the open air instead of through the mouthpiece), and if not rescued in a short time, may exhaust his supply of air and oxygen in the breathing bag, with the result that this bag may become so deflated as to be of insufficient buoyancy to keep the wearer afloat. Or, should the wearer be unconscious or dead when he reaches the surface the mouthpiece may become dislodged from his mouth and exposed to the sea, whereupon the breathing bag will simply flood, with complete loss of buoyancy to the appliance. In any of these contingencies, as will be appreciated, the person wearing the appliance will sink, without leaving any trace of his whereabouts, and this is regarded as a distinct drawback with existing forms of appliance of the type referred to.

The object of the present invention is to provide a modification of said existing forms of the appliance whereby this difficulty may in a simple and effective manner be met.

According to the present invention, a breathing appliance of the type referred to comprises, in combination, an inflatable breathing bag, a mouthpiece, a breathing tube connecting the mouthpiece and breathing bag, means for admitting a charge of respiratory gas to the breathing bag, means for absorbing carbon dioxide from the exhaled air, an inflatable buoyancy chamber additional to the breathing bag and integral therewith, a passage leading from the breathing bag to the buoyancy chamber and a non-return valve controlling said passage and

permitting flow of gas from the breathing bag to the buoyancy chamber for the inflation of the latter.

As will be appreciated, the provision, as above, of an additional buoyancy chamber provides in a simple manner against the contingencies referred to by serving to keep the wearer afloat even though he should, as stated, have exhausted the whole of his air and oxygen supply and thus the breathing bag should have become deflated and have lost its buoyancy, or, again, even if the breathing bag should have become flooded and for this reason have lost its buoyancy.

Moreover, with the additional buoyancy bag, the wearer of the appliance has no need to conserve his oxygen supply to ensure that he has sufficient to keep him afloat when he reaches the surface; he can use the whole of his oxygen for breathing purposes, relying on the additional buoyancy bag to keep him afloat.

The invention will now be further described with reference to the accompanying drawings which illustrate several embodiments by way of example, in which:

Figure 1 is a front elevation of a breathing appliance in accordance with the invention;

Figure 2 is a vertical cross-section through the appliance taken on the section line 2—2 of Figure 1;

Figures 3 and 4 are a front elevation of and vertical cross-section through a modified construction in accordance with the invention, and

Figures 5 and 6 are similar views showing a further modified construction.

Like reference numerals indicate like parts in the various figures.

The appliance, as shown in Figures 1 and 2, comprises a breathing bag in the form of a rubber envelope 10, communicating with a mouthpiece 11 by a flexible tubular connection 12.

Accommodated in a strap fitting 13 at the bottom of the envelope is a cylinder 14, of compressed oxygen, having a connection 15 to the envelope 10. This connection is controlled by a valve 16, and terminates, within the envelope, in a nozzle fitting 17, adapted to carry a small capsule 18 of compressed oxygen having a readily breakable neck 19 by which it is connected to the nozzle fitting 17.

Vulcanized on to the front face of the envelope 10 is an additional buoyancy chamber in accordance with the present invention, in the form of a collapsible envelope 20 of rubber. This envelope is arranged to be inflated from the breathing bag, the air entering the chamber by a non-

return valve 26 in the wall of the breathing bag, which valve may be of any convenient construction.

The envelope 20 may also be provided for its inflation with an inlet 21 through which gas, for example, breath from the user of the appliance, may be forced directly into the envelope.

A non-return relief valve 22 is fitted in the wall of the envelope to prevent its over-inflation.

10 In place of the inflation inlet 21, or in addition thereto, the buoyancy chamber may be arranged to be inflated in known manner by gas, for example, air, released from a small breakable capsule 23 containing the gas under pressure.

15 This capsule is mounted upon the inner face of a cap 24 screwed into a socket 25 vulcanized into the wall of the envelope.

20 The construction shown in Figures 3 and 4 is one in which two buoyancy chambers 27, 28 are provided interconnected by a passage-way 29. The chambers are inflated as in the previous construction by air from the breathing bag, the air entering the passage-way 29 by a non-return valve 26 in the wall of the breathing bag.

25 Figures 5 and 6 illustrate a further modification, in which the buoyancy chamber is incorporated in the lower part of the breathing bag envelope by the provision therein of a partition 30. As in the previous constructions, the buoyancy chamber is inflated by air from the breathing bag envelope, and for this purpose a non-return valve 26 is provided in the partition 30.

30 In the two modified constructions illustrated respectively in Figures 3 and 4 and Figures 5 and 6, the buoyancy chamber, may, if desired, be fitted, as in the construction first described, with a direct-inflation inlet 21 (shown in chain line), or with a breakable compressed gas capsule 23 (also shown in chain line), or with both.

35 As will be appreciated, the provision of a direct-inflation inlet 21 or a breakable compressed gas capsule 23, in addition to a non-return valve 26 in the wall of the breathing bag envelope, enhances the utility of the appliance. Thus, for 40 instance, if circumstances permit, the wearer of the appliance can initially inflate the buoyancy chamber by exhaling his breath into the inlet 21, and this initial inflation through the inlet 21 will serve to reduce the consumption of oxygen or air from the breathing bag for buoyancy purposes. Again, the same result may be achieved by breaking the gas capsule 23, in the event of 45 circumstances not permitting the wearer of the appliance to inflate the buoyancy chamber by blowing through the inlet 21. Moreover, if the non-return valve 26 should become inoperative for any reason, so that air is prevented from passing it from the breathing bag to the buoyancy chamber, the wearer can use either of his alternative inflation means, according to desire or as 50 circumstances permit.

5 It is to be understood, however, that although, generally speaking, for example, for the reason just referred to, it is desirable to provide, in addition to the non-return valve 26, for the inflation of the buoyancy chamber, a direct-inflation inlet (21) or/and a breakable gas capsule (23), these supplementary inflation means may, if desired, be omitted.

10 It will be observed that the invention is capable of considerable variation in the precise form and position employed of the buoyancy chamber, and in other structural details without departing from the scope and spirit of the invention.

15 What I claim is:—

1. A self-contained breathing appliance for 15 submarine use, comprising, in combination, an inflatable breathing bag, a mouthpiece, a breathing tube connecting the mouthpiece and breathing bag, means for admitting a charge of respiratory gas to the breathing bag, means for absorbing carbon dioxide from the exhaled air, an inflatable buoyancy chamber additional to the breathing bag, a passage leading from the breathing bag to the buoyancy chamber and a non-return valve controlling said passage and permitting flow of gas from the breathing bag to the buoyancy chamber for the inflation of the latter. 20

2. A self-contained breathing appliance for 30 submarine use, comprising, in combination, an inflatable envelope, a partition therein dividing the interior of the envelope into two separate compartments, one of which compartments constitutes a breathing bag and the other a buoyancy chamber additional thereto, a mouthpiece, a breathing tube connecting the mouthpiece and the breathing bag, means for admitting a charge of respiratory gas to the breathing bag, means for absorbing carbon dioxide from the exhaled air, a passage leading from the breathing bag to the buoyancy chamber for the inflation of the latter. 35

3. A self-contained breathing appliance for 40 submarine use, comprising, in combination, an inflatable breathing bag, a mouthpiece, a breathing tube connecting the mouthpiece and breathing bag, means for admitting a charge of respiratory gas to the breathing bag, means for absorbing carbon dioxide from the exhaled air, an inflatable buoyancy chamber mounted upon the exterior of the breathing bag, a passage leading from the breathing bag to the buoyancy chamber and a non-return valve controlling said passage and permitting flow of gas from the bag to the chamber for the inflation of the latter. 45
